(57) **CLAIM**

I claim the ornamental design for a metal rod, as shown and described.

DESCRIPTION

FIG. 1 is a front, right side and top perspective view of metal rod, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged top plan view thereof;

FIG. 7 is an enlarged bottom plan view thereof; and,

FIG. 8 is a partial enlarged view of FIG. 1.

The dashed lines in the figures illustrate portions of the metal rod that form no part of the claimed design. The dash dot dash lines in FIGS. 1 and 8 are for the purpose of illustrating the enlarged view indicators and form no part of the claimed design.
